(57) **CLAIM**

We claim the ornamental design for a media tray and display, as shown and described.

DESCRIPTION

FIG. 1 is a top perspective view of one embodiment of a design of a media tray and display of the present invention in a first position;

FIG. 2 is a top plan view thereof;

FIG. 3 is a front elevational view thereof;

FIG. 4 is a left-end elevational view thereof;

FIG. 5 is a right-end elevational view thereof;

FIG. 6 is a rear elevational view thereof;

FIG. 7 is a bottom plan view thereof; and,

FIG. 8 is a top perspective view of the media tray and display of FIG. 1 in a second position.

The broken lines immediately adjacent the shaded areas represent the bounds of the claim and all other broken lines are for illustrative purposes only. None of the broken lines form a part of the claimed design.
